UNITED STATES PATENT OFFICE.

HINSDALE SMITH, OF SPRINGFIELD, MASSACHUSETTS.

VEHICLE-BODY.

SPECIFICATION forming part of Letters Patent No. 781,850, dated February 7, 1905.

Application filed May 17, 1904. Serial No. 208,417.

To all whom it may concern:

Be it known that I, HINSDALE SMITH, a citizen of the United States of America, and a resident of Springfield, in the county of Hampden and State of Massachusetts, have invented 5 certain new and useful Improvements in Vehicle-Bodies, of which the following is a full, clear, and exact description.

This invention relates to improvements in 10 the construction of vehicle-bodies, and more especially those designed to support and carry front and rear double seats.

An object of the invention is to provide a vehicle-body which is composed mostly of metal 15 and which is nevertheless comparatively light, but very strong and also devoid of projections constituted by fastenings, more especially externally of the body, whereby a vehicle-body of slight and very attractive appearance may be produced.

Another object is to provide special fittings and appliances and to combine the same in the vehicle-body structure and with the backs adjacent the rear-seat bottoms.

25 In the drawings illustrating the improved vehicle-body, Figure 1 is a plan view. Fig. 2 is a sectional elevation as taken on the line 2 2, Fig. 1. Fig. 3 is a cross-section looking rearwardly beyond the line 3 3, Fig. 1. Fig. 30 4 is a perspective view, on a larger scale, showing structural features and combinations in the part of the body adjacent the rearwardly-entering door. This peculiar view shows the parts as seen looking in the direction of the arrow and beyond the section-line 4 4, Fig. 1. Figs. 5 and 6 are a sectional and rear view of a form of bracket employed.

Similar characters of reference indicate corresponding parts in all of the views.

The invention consists in constructions, combinations, and arrangements of parts, all substantially as hereinafter fully described, and set forth in the claims.

45 The main portion or underbody A is in the form of a rectangular box, the rear wall of which is inclined from the vertical and provided with a doorway or entrance-opening *a*, for which a hinged door is to be provided, the 50 same not shown. The body A is constructed

of upper and lower rectangular frames 10 and 12, of steel or angle-iron, having the horizontal flanges 14 thereof inwardly projecting, while the vertical flanges 15 constitute backs, against the inner surfaces of which are fitted 55 panels 16, of sheet metal, preferably aluminum, the connections being made by riveting, as represented at 17. The forward part of the underbody A, back, however, from the dashboard-supporting extension *b*, is cross-braced by the pair of arches or girders *d* and *e*, made of angle-bars and aluminum panels riveted thereto, as represented in Figs. 1, 2, and 3, these girders or transverse arches stiffening and transversely tying the body and 60 constituting supports for the pair of front seats represented by dotted lines at *f*, *f*. Upright angle-bars 19 19 are provided at the rear corners, and vertically-applied angular or other formed bars 20 20, one of which is 70 shown in Fig. 4, are provided at the portion of the underbody back next to the doorway or rear opening *a* thereinto.

B B represent the bottoms for the rear duplicated seats, of which C C represent the 75 backs. The rear seats, as represented in Figs. 1, 2, and 3, are rounded and swelled outwardly and rearwardly, and the bottoms B B are constituted by boards having the shapes more particularly shown in Fig. 1 80 and which are secured on and to the upper angle-bars of the underbody by the bolts 22, the said boards overhanging both inwardly and outwardly the sides and rear end of the underbody. The aluminum panels 24, curved 85 to conform to the external edge of the seat-bottoms B, have at their upper and lower edges the angle-bars 25 35, to the vertical members of which the panels are marginally riveted, and the lower angle-bars 35 are fastened to the seat-bottom boards.

The inwardly-overhanging portions of the seats and backs B and C are supported and reinforced by parts as follows, it being pointed out that the backs have at the corners adjacent the doorway-opening *a* the more or less nearly vertical angle-bars 26 26, an inwardly-extending bracket *g*, and an outwardly-extending bracket *h*, having their straight adjacent faces abutted against and to hold in a clamp- 95 100

like manner the marginal portions of the panels 16^a 16^a and the flange-like members of the vertical bars 20, the bolts 27, with confining-nuts, holding the parts together. The 5 brackets *h* are, as shown, formed hollow—that is, they are each constructed with a back 30, a top or shelf-like member 32, and opposite side cheeks 33 33. After fastening-bolts are inserted through the back 30 of the bracket 10 the thin metallic curved strip 34 is soldered, brazed, or otherwise fastened to the rear edge portions of the chambered bracket-casting, giving to the bracket a flush and slightly rear edge. The seat-bottoms are by the bolts 21 15 secured by being passed and fastened vertically through the inner horizontal extremities of the inner brackets *g*.

The bottom angle-bars 35 at the junction of the seat-bottoms have their extremities bolted, 20 as indicated at 36, to the outer extremities of the outer brackets, such bolts at 36 having the heads thereof concealed within the chambered and inclosed brackets *h*, and such bars extend externally around the backs and forwardly throughout the whole length of each thereof, having connection with the panels of the backs and with the seat-bottom boards by rivets, bolts, or other appropriate fastenings.

An approximately triangular gusset or connecting-plate *j* is provided to range in a general fore and aft direction and to have a location at the junction of the lower portion of the upright angle-bar 26 with the seat-bottom board B. This gusset-plate *j* is by the screws 30 35 40 40 near its lower edge fastened to the seat-bottom B, and its rear upright edge 43 is formed with a rabbet, as shown in Fig. 4 and also in Fig. 1, so as to match with and have its outer face flush and continuous with the inwardly-extending flange-like portion of the upright angle-bar 26, connection of the matched-together parts being made by the line of riveting 45 40 43 42.

The rear divided wall of the underbody at 45 both sides of the doorway-opening *a* has provided within the aluminium panels the diagonally-arranged metallic bars *k*, the extremities of which are riveted to the upright angle-bars 19 at the corners of the underbody 50 and the upright bars 20 20 at the boundaries of the doorway-opening and which bars 20 20 are continuous substantially in the line of the upright bars 26 for the seat-backs.

To the bars 20 and 26 are secured, at one 55 side of the doorway-opening at the rear of the body, the metallic lugs *m m*, to which the rear door may be hinged. The underbody is designed to receive therein and support on the horizontal flange-like members of the angle-bars 12 12 a suitable flooring, which may be either of wood or metal and which is not here illustrated.

The parts comprising the duplicated seat-bottom boards and rounded metallic backs 60 65 provide in the described structure a two-part

tonneau, which, as occasion may render desirable, may be removed, leaving the body with only the front double seats, so that the space in the underbody to the rear thereof may be utilized otherwise than for carrying persons. 70 The seats both front and rear are of course to be cushioned and upholstered, and the body externally is to be painted, varnished, and decorated in whole or in part, or it may be polished and finished in the natural metal, in 75 either case rendered attractive and slightly, and especially so by the flush and continuous surfaces produced in consequence of the construction and arrangement of the parts making and strengthening the frame of the body, 80 the rear seats, and the backs for the latter.

Having thus described my invention, what I claim, and desire to secure by Letters Patent, is—

1. In a vehicle-body, a rectangular underbody composed of upper and lower rectangular frames, each constituted by angle-bars vertically-extending bars connecting the one of said frames with the other, one or more transverse girder-arches extending from side 90 to side of the structure and connected with the upper and lower angle-bar frames, and sheet-metal panels riveted to the vertical members of the angle-bar frames.

2. In a vehicle-body, the combination with 95 the underbody constituted by upper and lower frames comprising angle-bars and intermediate sheet-metal panels riveted to the vertical members of the angle-bars, and vertical connections between the upper and lower angle-bar frames, of the duplicated seat-bottoms and backs united to the bodies, said bottoms having internal portions thereof resting on the upper frame of the underbody and fastened thereto and overhanging side and 100 rearward portions of the underbody.

3. In a vehicle-body, in combination, the underbody-section of rectangular form, composed of upper and lower frames, and intermediate panels riveted thereto, and provided with an opening at its middle rear portion, having at the margins thereof vertical metallic bars connecting upper and lower members of the aforesaid upper and lower frames, the seat-bottoms made with rounded, rearwardly-disposed backs, having forward extensions, said bottoms resting on the underbody, and secured thereto, and pairs of inwardly and outwardly arranged brackets formed as parts of the said vertical metallic bars and supporting the seat-bottoms both forward and at the rear of the underbody-back.

4. In a structure of the character described, the combination with the underbody comprising top and bottom frames composed of 115 angle-bars and intermediate sheet-metal panels and having at the rear end a doorway with vertical metallic bars at each side thereof extending from top to bottom of the underbody, of the separate and duplicated seat- 120 125 130

bottoms and connected rounded backs supported on and outwardly overhanging the upper frame of the underbody, and comprising the bottom boards, the upper and lower metallic bars, and the intermediate sheet-metal panels, the said bottom boards being bolted to the upper metallic frame of the underbody, and inner and outer brackets having vertical members thereof secured to the vertical metallic bars at the sides of the doorway, the seat-bottoms being supported on the inner brackets, and the lower metallic bars of the seat-backs being bolted to the tops of the rearwardly-extending outer brackets.

5 5. In a structure of the character described, the combination with the underbody comprising a top frame composed of angle-bars, and having at its back a doorway, and rearwardly-extending brackets at each side of such doorway, of the separate and duplicated seat-bottoms and connected rounded sheet-metal backs supported on and outwardly overhanging the upper frame of the underbody, and comprising the bottom boards, the upper and lower metallic bars and the intermediate panels, the said bottom boards being bolted to the upper metallic frame of the underbody, the ends of the lower metallic bars being secured to the said brackets to the rear of the 20 underbody-back.

30 6. In a structure of the character described, the underbody composed of upper and lower angle-bar frames, and intermediate sheet-metal panels, and having a door-opening at its rear end, and the vertical metallic bars 20 20 at the sides of said opening connecting the upper and lower frames, the inner and outer brackets *g* and *h* arranged back to back at the opposite sides of said vertical bars and having 35 bolts passed through both their backs and through the vertical bars, the seat-bottoms and connected rounded sheet-metal backs having the upper and lower metallic bars 25, and 35, end portions of the latter adjacent said 40 door-opening being secured by vertically-applied bolts to the top of the rearwardly-extending outer brackets, and the seat-boards being secured by vertically-applied fastenings to the upper angle-bar frame of the underbody, and to the inner brackets.

45 7. In a structure of the character described, the combination with the underbody comprising top and bottom frames composed of angle-bars and having at the rear end a doorway 50 with vertical metallic bars at each side thereof extending from top to bottom of the underbody, of the separate and duplicated seat-bottoms and connected rounded backs supported on and outwardly overhanging the upper 55 frame of the underbody, and comprising the bottom boards, the upper and lower metallic

bars, 25 and 35, the upright metal bars 26 and the intermediate sheet-metal panels, the said bottom boards being bolted to the upper metallic frame of the underbody, and inner and outer brackets having vertical members thereof secured to the vertical metallic bars at the sides of the doorway, the seat-bottoms being supported on the inner brackets, the lower metallic bars of the seat-backs being bolted 65 to the tops of the rearwardly-extending outer brackets, and the triangular metallic gussets 70 fastened to said upright bars 26 and to the inner rear edge portions of the said boards.

8. In a structure of the character described, 75 the underbody composed of upper and lower angle-bar frames, and intermediate sheet-metal panels, and having a door-opening at its rear end, and the vertical metallic bars 20 20 at the sides of the opening connecting the upper and lower frames, the inner bracket *g* and outer bracket *h* constructed hollow, and said brackets arranged back to back at the opposite sides of said vertical bars and having bolts 80 passed through the backs of both brackets 85 and through the vertical bars, the closing-strips 34 at the rear edges of the outer brackets the seat-bottoms and connected rounded sheet metal backs having the upper and lower metallic bars 25 and 35, end portions of the 90 latter adjacent said door-opening being secured by vertically-applied bolts to the top of the rearwardly-extending hollow outer brackets, and the seat-boards being secured by vertically-applied fastenings to the upper angle-bar 95 frame of the underbody, and to the inner brackets.

9. In a structure of the character described, in combination, the underbody having at its back the door-opening, and provided at the boundaries thereof with upright metallic bars, the brackets *g*, and the brackets *h*, of hollow construction, the pairs of said brackets being arranged back to back at the rear and front sides of said upright bars and having therefor 100 the horizontally-connecting bolts 27 with fastening-nuts, the seat-bottoms and connected rounded backs resting on the upper edges of the rear opposite portions of the underbody and secured thereto, and also resting on said 105 brackets and having for the connection thereof with said brackets vertically-applied bolts 21 and 36, each bolt 36 being inclosed within the hollow bracket, and said hollow brackets having the flush strips secured to their rear 110 edges, closing the openings therein.

Signed by me at Springfield, Massachusetts, in presence of two subscribing witnesses.

HINSDALE SMITH.
